UNITED STATES PATENT OFFICE.

JOHN F. BARKER, OF SPRINGFIELD, MASSACHUSETTS, ASSIGNOR TO THE
GILBERT & BARKER MANUFACTURING COMPANY, OF SAME PLACE.

GAS-BURNER.

SPECIFICATION forming part of Letters Patent No. 628,063, dated July 4, 1899.

Application filed December 12, 1898, Serial No. 698,954. (No model.)

To all whom it may concern:

Be it known that I, JOHN F. BARKER, a citizen of the United States of America, residing at Springfield, in the county of Hampden and State of Massachusetts, have invented a certain new and useful Improvement in Gas-Burners, of which the following is a description, reference being had to the accompanying drawings, wherein—

10. Figure 1 is a plan view of a burner embodying said improvement. Fig. 2 is a view of a portion of the parts shown in Fig. 1 in central longitudinal horizontal section.

The improvement belongs to that class of 15 gas-burners in which the gas is consumed in the shape of a pencil of flame for the purpose of utilizing its heat in various processes of manufacture—as, for instance, in the jewelers' art. In gas-burners of this class the gas, 20 whether it be carbureted hydrogen or a hydrocarbon, such as is commonly produced from gasolene, is generally mixed with atmospheric air, both being under pressure, before it reaches the point of combustion, and the apparatus herein shown is designed for that use.

25 In the accompanying drawings the letter *a* denotes a central gas-conducting pipe—that is, located centrally within another—which has a burner end *a'*.

30 The letter *b* denotes the outer annular pipe, which incloses the said central pipe *a*. It is closed at the rear end and suitably shaped at the front or burner end. There is a small valve-orifice *c* leading from the interior of 35 the inner pipe to the interior of the outer pipe, the passage of gas through which is adjust-

ably controlled by the adjustable valve *d*, the stem of which is preferably a screw.

The gas may enter at *e* and the air at *f*. They meet, mix in the chamber *g*, and the mixed air and gas travels into the central gas-conducting pipe to the point of combustion at the burner end. If, with matters in this condition, the operator slightly opens the valve *d*, a portion of the gas flows through the valve-orifice, fills the outer pipe *b*, and, proceeding to the open end, is consumed along with the gas which escapes from the burner end of the pipe *a*, at the same time covering that volume of gas which is escaping from pipe *a* with an outer gaseous envelop of greatly-diminished velocity, with the result of making the volume under consumption in the shape of a pencil much steadier and more reliable in every way than would otherwise be the case, and the opening of the valve alters the relative pressures of the mixed air and gas to great practical advantage.

I claim as my improvement—

In a burner, the combination with the pipe 60 *a* having burner end *a'* at one extremity and mixing-chamber *g* at the other, and means for supplying air and gas to said chamber; of the annular pipe *b* surrounding pipe *a* and having a burner end coincident therewith, an 65 orifice *c* connecting said pipes remote from the burner, and a valve therefor, as and for the purpose set forth.

JOHN F. BARKER.
